ROLL SUPPORTING AND DISPLAY RACK

Filed May 12, 1926

Fig. 2.

Inventor:
Alfred E. Holmes,
By Dreyerforth, Lee, Chittenden & Hall,
Attorneys.

UNITED STATES PATENT OFFICE.

ALFRED E. HOLMES, OF CHICAGO, ILLINOIS, ASSIGNOR TO ALEXANDER H. REVELL & CO., OF CHICAGO, ILLINOIS, A CORPORATION OF ILLINOIS.

ROLL SUPPORTING AND DISPLAY RACK.

Application filed May 12, 1926. Serial No. 108,537.

This invention relates particularly to a rack adapted to display and support safely rolls of linoleum, or the like; and the primary object is to provide a very simple store fixture of this character equipped with adjustably mounted roll-engaging devices, enabling the rack to be used to capacity, regardless of variation in the diameters of the rolls of linoleum, or carpet.

10 The invention is illustrated in its preferred embodiment in the accompanying drawing, in which—

Fig. 1 represents a broken perspective view of the improved display rack supported 15 on a floor; and Fig. 2, a broken vertical sectional view taken as indicated at line 2 of Fig. 1.

In the preferred embodiment illustrated, the rack comprises a central horizontal bar 20 A mounted on standards A' secured to the floor, indicated at A²; bars B parallel with and flanking the bar A and spaced a suitable distance therefrom; and shiftable roll-engaging devices C pivotally and slidably 25 mounted on the bars B.

The rack preferably is composed of pipes and fittings. Thus, the central bar A may comprise pipe-sections 1 and fittings 1^a; and the standards A' may comprise pipes connected at their upper ends with said fittings and equipped at their lower ends with floor-plates 2 (one shown), secured to the floor by means of screws 2^a. Also, the bars B may comprise pipe-sections 3 and fittings 3^a, the 35 fittings 3^a being supported by short transverse pipe-sections 4 carried by the fittings 1^a. The central pipe-sections and supporting standards may be of larger diameter than the pipe-sections which form the bars B 40 and arms 4.

The standards A' are of a height somewhat greater than the length of the rolls D (one shown). Thus, the rolls may be supported upon end upon the floor and may project partially beneath the outer bars 3. The rack may be of any suitable length, and may be equipped with any desired number 45 of roll-engaging devices C. Each roll-engaging device preferably comprises a slide 5 pivotally and slidably mounted on a bar B; an outwardly projecting arm 6 carried by the slide 5 and having a downturned end-portion 6^a affording a pin which is adapted to depend into the roll; and an inwardly 50 extending arm 7 having a curved extremity 55

7^a adapted to engage the lower side of the center bar A. The arm 7 may be swung downwardly to lift the pin 6^a from the roll.

It is customary to ship linoleum, for example, in rolls, linoleum being wound upon 60 a central pasteboard tube 8. This provides a central opening in the roll into which the pin, or stud, 6^a, may depend.

In the use of the improved rack, the rolls are supported upon end upon the floor 65 with their centers at the vertical planes of the roll-engaging pins 6^a. The inner portions of the rolls may project inwardly past the planes of the outer bars 3, where the rolls are of large diameter. The roll-engaging devices C may be shifted longitudinally on the bars 3, thus enabling the rolls 70 to stand close together, regardless of their diameters.

The rack should be of sufficient height to 75 allow a clearance of a few inches above the rolls. When it is desired to withdraw a roll from the rack, as when a sale of linoleum is to be effected, all that is necessary is to lift the centering pin 6^a and tip the roll away 80 from the plate of the rack. Thus, the roll can be laid upon the floor and the desired length of linoleum can be measured and cut from the roll.

The rack is open at the sides. That is, 85 there is no obstruction, after the centering pin is lifted, to prevent the roll from being swung outwardly and downwardly about its outer lower corner.

The arm 7 of the roll-engaging device C 90 serves normally to hold the device in the position illustrated in the figures, in which position the centering pin 6^a is vertical.

The arm 7 is, in effect, a stop arm which 95 prevents the arm 6 from swinging below a horizontal position.

The foregoing detailed description has 100 been given for clearness of understanding only, and no unnecessary limitations should be understood therefrom, but the appended claims should be construed as broadly as permissible, in view of the prior art.

What I regard as new, and desire to secure by Letters Patent, is:

1. A rack of the character set forth, comprising supporting standards, a pair of parallel bars supported thereon, and roll-engaging devices pivotally and slidably mounted on one of said bars and equipped with means for engaging the other of said bars to 105 110 115

prevent rotation beyond the desired point.

2. A rack of the character set forth, comprising supporting standards equipped with base-plates adapted to be secured to a floor, 5 a substantially horizontal bar carried by said standards, and a plurality of roll-engaging devices slidably and rotatably mounted on said bar and equipped with centering pins adapted to enter the upper ends of rolls sup- 10 ported on the floor, and stop-devices serving to limit the rotation of said roll-engaging devices.

3. A rack of the character set forth, comprising supporting standards, a substantially 15 horizontal bar mounted thereon, a parallel bar spaced with respect thereto, and members pivotally and slidably mounted on said

second-mentioned bar, said members being equipped at one side with arms carrying roll-engaging pins and at the other side with 20 stop-arms engaging said first-mentioned bar.

4. A rack comprising a central substantially horizontal bar, standards supporting said bar, arms projecting laterally from said bar at the front and rear sides thereof, parallel bars carried by said arms, and roll-engaging devices slidably and rotatably mounted on the outer bars, said devices having outwardly extending arms equipped with 25 depending roll-centering pins and having 30 inwardly extending arms engaging the lower side of said first-named bar.

ALFRED E. HOLMES.
